COLUMBIA PLANOGRAPH CO., WASHINGTON, D. C.

UNITED STATES PATENT OFFICE.

NELLIE M. MILLER AND GEORGE R. EVANS, OF WASHINGTON, DISTRICT OF COLUMBIA.

STREET-SWEEPER.

1,094,235.

Specification of Letters Patent. Patented Apr. 21, 1914.

Application filed June 19, 1912. Serial No. 704,622.

To all whom it may concern:

Be it known that we, NELLIE M. MILLER and GEORGE R. EVANS, citizens of the United States, residing at Washington, in the District of Columbia, have invented certain new and useful Improvements in Street-Sweepers; and we do hereby declare the following to be a full, clear, and exact description of the invention, such as will enable others skilled in the art to which it appertains to make and use the same.

This invention relates to improvements in street sweepers generally although the invention relates more particularly to improvements upon the patent to Miller No. 1,003,937, issued September 19, 1911.

The principal object of the invention is to improve the construction of street sweepers and to provide a simple, efficient and comparatively inexpensive machine adapted to sweep the dust or dirt into a wagon body whereby the same may be transported to any desired place and later dumped.

Another object of the invention is to provide a street sweeper in which the sweeping means is yieldably supported from a wagon body whereby all shocks and jars incident to the travel of the sweeper over rough streets will be eliminated.

A further object of the invention is to provide a street sweeper of the character described in which means are provided for readily raising the sweeping means above the ground when it is desired to transport the sweeper from place to place.

With these and other objects, the invention consists in the construction and novel combination of parts hereinafter fully described, illustrated in the accompanying drawings and pointed out in the claims hereinafter appended; it being understood that various changes in the form, proportion, size and minor details of construction within the scope of the claims may be resorted to without departing from the spirit or sacrificing any of the advantages of the invention.

In the drawings Figure 1 is a top plan view of a street sweeper constructed in accordance with our invention, Fig. 2 is a side elevation of the left hand side of the machine, Fig. 3 is an enlarged partial side elevation of the right hand side of the machine, Fig. 4 is a longitudinal sectional view through the machine, Fig. 5 is a transverse sectional view taken on the line 5—5 of Fig.

4, looking in the direction indicated by the arrows, and Fig. 6 is a transverse sectional view taken on the line 6—6 of Fig. 2, looking in the direction indicated by the arrows.

Like reference numerals designate corresponding parts in all the figures of the drawings.

Referring to the drawings, the invention comprises broadly a dumping wagon which is indicated as a whole by the reference letter A, and a sweeping means which is indicated as a whole by the reference letter B.

The dumping wagon A includes a body which consists of side-boards 5—5, a front end board 6 which depends below the side boards 5 and a rear end portion 7, the latter consisting of an upper board 7^a and a lower board 7^b, said lower board being disposed in advance of the upper board. The rear ends of the side-boards 5, and the boards 7^a and 7^b of the rear portion 7 are connected by a transverse bridge 8. A rear axle 9 is mounted in suitable bearings 10 which depend from the bridge 8, said axle carrying the ground wheels 11—11. A bottom 12 made up of downwardly and outwardly oppositely inclined sections is connected to the lower edge of the front end wall 6 and the lower edge of the lower board 7^b of the rear portion 7. It will thus be observed that by means of this construction, spaces are formed between the side edges of the bottom 12 and the lower edges of side-boards 5, and that dirt or other material within the body is directed outwardly through said openings through the medium of the substantially V-shaped construction of said bottom.

In order to close the openings, there are provided doors 13—13 which are hingedly connected, as at 14, to the side board 5 of the body, the lower edges of the doors abutting the side edges of the bottom when said doors are in their closed positions. A longitudinally disposed shaft 15 is centrally disposed within the wagon body above and in spaced relation to the apex 12^a of the bottom. The front end of the shaft is journaled in a bearing 16 which is supported centrally upon the bridge 8, and the rear end of said shaft is journaled in a bearing 17 which is centrally carried by the front end board 6 of the body.

The front end of the shaft furthermore projects through an opening in said front board 6 and is provided on its projecting end with a 110

ratchet 18 of suitable construction together with an actuating lever 19 by means of which the shaft may be rotated and locked at any desired point of rotation. Centrally secured to each door 13 and adjacent the lower edge thereof is an eye 20, and to each eye is connected one end of a chain 21, the other end of said chains being fixedly connected to the shaft 15 so that upon rotation of said shaft in one direction the chains will be wound therearound and consequently will hold the doors 13 against outward swinging movement.

The sweeping means B includes a pair of spaced arms 22-22 which extend rearwardly from the wagon A and have their forward ends suitably journaled upon the axle 9. Journaled in the rear ends of the arms 22 is a transversely disposed shaft 23, and upon this shaft is fixedly connected a rotary brush 24 of any suitable construction. The sweeping means furthermore includes an inclined casing which is designated as a whole by the reference numeral 25 and consists of a bottom 26 and spaced side walls 27-27, said casing extending forwardly and upwardly through a vertical slot which is centrally formed in the upper section 7^a of the rear end board 7. The upper or forward end of the casing is supported for pivotal movements upon a transversely disposed drive shaft 28 which is supported in suitable bearings 29-29 carried by the side-boards 5 of the body, said shaft extending through the side walls 27-27 of the casing. Supported by the side walls 27 of the casing intermediate the shafts 23 and 28 is a counter-shaft 30. A conveyer apron 31 of any suitable construction is operatively connected to the shafts 28 and 30. The bottom 26 of the casing below the counter-shaft 30 is curved upwardly, as at 32, and thence extends rearwardly and downwardly to form an apron 33 which is disposed in front of the brush 24. The side walls 27 above the shaft 30 project upwardly and support a transversely disposed spring actuated shutter 34. The spring for this shutter is indicated as a spring hinge 35^a, it being understood that the showing is merely typical of any suitable form of spring hinge or spring adapted to properly hold the shutter in position yieldably. A hood 35 is disposed around the brush 24 and terminates in an upwardly extending portion 36, said portion extending to the shutter 34 and co-operating therewith and with the apron 33 to form a passage for guiding the dust or dirt from the brush 24 to the conveyer apron 31.

In order to drive the shaft 28 from the ground wheels 11, one of said wheels carries a drive gear 37 which meshes with a pinion 38 which is splined and slidably mounted upon said shaft 28. This pinion is

formed with a toothed hub 39 which is adapted to be clutched with a toothed hub 40 of a sprocket wheel 41 which is loose on said shaft 28. The sprocket wheel 41 is connected by means of a chain 43 to a sprocket wheel 42 which is fixed on the brush shaft 23. It will thus be observed that by the means above described, the conveyer apron 31 and the brush 24 are driven from the drive gear 37, and that the conveyer apron 31 is always in action when the wagon is in motion, while the brush 24 is only actuated upon the hub 40 being engaged by the hub 39.

In order to shift the hub 39, and consequently actuate the brush 24, a pair of upper and lower brackets 44 and 45 respectively are carried by the adjacent side-board 5 of the wagon body, and supported in said brackets in a vertical rock-shaft 46. A shipper lever 47 is fixedly connected at one end to the upper end of this shaft, and this lever has its other end engaged in the usual manner with the hub 39 of the pinion 38. Secured to the lower end of the shaft 46 is a rocker-arm 48, and this arm is connected to one end of a forwardly extending rod 49. The forward end of the rod 49 is pivotally connected, as at 50, centrally of a hand-lever 51 which is fulcrumed, as at 52, upon the side-board 5 of the body. A rack 53 is associated with the lever 51, and this lever includes the usual pawl which is designated as a whole by the reference numeral 54, and which is adapted for engagement with said rack to hold the hub 39 into or out of engagement with the hub 40.

In order to yieldably support the brush 24 upon the ground, or to elevate said brush above the ground, a bell-crank lever 55 is fulcrumed at its angle, as at 56, to the rear end of one side-board 5 of the body. A pin 57 is pivotally connected at one end, as at 58, to the rearwardly extending horizontal arm 55^a of said lever. This pin extends downwardly through a vertical slot formed in a cross bar which connects the arms 22, and is provided on its lower end with a nut 59 and adjacent its upper end with a nut 60, both of said nuts being disposed in spaced relation to the arm 22. Upper and lower coil springs 61 and 62 are respectively disposed around the pin above and below the arm 22 and between the nuts 59 and 60. A hand-lever 63 is fulcrumed upon the forward end of the adjacent side-board 5 of the body, and this lever is connected to the vertical arm 55^b of said bell-crank lever 55 by means of a rod 64. A rack 65 is associated with the lever 63, and carried by said lever and engageable with the rack is a pawl which is indicated as a whole by the reference numeral 66.

In operation, as the machine is drawn along over a street, the lever 63 is released

so as to position the brush 24 upon the ground. The hand-lever 51 is shifted forwardly so as to engage the hub 40 by the hub 39, and thereby operatively connect said brush 24 with the gear wheel 37 as above described. The dirt will be thrown upwardly into the casing 25 by the brush 24, said dirt first passing onto the apron 33 and thence into the curved portion 32 of the bottom 26 of said casing. The strips 31^a of the conveyer apron 31 will then carry the dirt upwardly along the bottom 26 of the casing to the upper end thereof, at which point the dirt will be discharged into the wagon body 10

15 A through the medium of a chute 67 which is formed from a continuation of the bottom 26 of said casing. This chute has its sides 67^a—67^b bent downwardly so as to direct the dirt on opposite sides of the bottom 12 of 20 said body, and carried by the forward end of the chute 67 is a bearing plate 68 which rests upon the shaft 15 and thereby supports the lower edge of the chute. When it is desired to dump the dirt from the body, 25 the hand-lever 19 is actuated to release the chains 21. The dirt within the body being directed outwardly due to the inclined bottom 12 will exert a sufficient pressure against the doors 13 to swing the same open, there- 30 by permitting the dirt to be readily discharged. While the machine is being transported the hand-lever 63 is moved forwardly, and as a result, the arms 22 and consequently the brush 24 will be elevated 35 above the ground. It is to be noted that when the brush 24 is working upon the ground, said brush is yieldably held into engagement therewith by means of the coil springs 61 and 62, and that whenever the 40 brush 24 strikes a stone or other obstruction, the springs will yield to such an extent as to permit of the brush passing there-

over in such a manner as to eliminate the possibility of shocks and jars to the mechanism.

45

In order to permit of the wagon backing or turning without reversing the conveyer apron and brush, the wheels 11 are each connected to the axle 9 by means of a pawl and ratchet mechanism, one of said mechanisms only being shown and designated as a whole by the reference numeral 69.

50

What is claimed is:

1. In a street sweeper, a vehicle, a sweeping brush supported from said vehicle for rotation, a hood covering said brush, an open topped inclined casing extending upward from the lower rear end portion of the hood, a conveyer provided with flights arranged to force material up said casing, and means to close the upper rear portion of the hood, said means being yieldable to permit passage of the conveyer flights.

55

2. In a street sweeper, a vehicle, a sweeping brush supported from said vehicle for rotation, a hood covering said brush, an open topped inclined casing extending upward from the lower rear end portion of the hood, a conveyer provided with flights arranged to force material up said casing, and means to close the upper rear portion of the hood, said means being yieldable to permit passage of the conveyer flights, and comprising a shutter hinged to the upper rear edge of the hood and provided with a spring normally holding the shutter closed.

60

In testimony whereof, we affix our signatures in presence of two witnesses.
